UNITED STATES PATENT OFFICE.

ERNEST C. WILCOX, OF MERIDEN, CONNECTICUT, ASSIGNOR TO THE CONNECTICUT TELEPHONE & ELECTRIC COMPANY, OF MERIDEN, CONNECTICUT, A CORPORATION OF CONNECTICUT.

IGNITION SYSTEM.

1,251,314.

Specification of Letters Patent. Patented Dec. 25, 1917.

Application filed August 17, 1915. Serial No. 45,859.

To all whom it may concern:

Be it known that I, ERNEST C. WILCOX, a citizen of the United States of America, residing at Meriden, Connecticut, have invented a new and useful Ignition System, of which the following is a specification.

This invention relates to engines having a relatively large number of cylinders, and the general objects of the invention are to 10 provide simple, practical and reliable means for the regular ignition of the charges in such engines.

On account of the number of cylinders and the high speed at which these engines 15 operate, certain difficulties have heretofore been experienced, particularly in respect to the timing of the firing in the different cylinders, and the rapid production of sufficiently intense igniting sparks. These difficulties I have overcome in my present invention by providing a number of induction coils, commensurate with the number of cylinders, each coil serving as many cylinders as it reliably can without overloading, 20 the firing current being transmitted from each coil to the cylinders which it serves through a distributor, and the timing of the firing in the cylinders being determined absolutely and invariably by circuit breakers, 25 said circuit breakers being operated in proper synchronism by cams all on the same single engine-driven cam shaft.

The distributors may be operated by the cam shaft, or one distributor may be operated by the cam shaft and the other distributor or distributors be operated by separate engine-driven shafts, the distributors in this latter instance being coupled together so as to be shifted in unison upon the 30 advance or retardation of the spark.

Other features of my invention will appear as the specification proceeds.

In the accompanying drawings I have 45 illustrated a practical embodiment of my invention applied in this instance to the ignition of a twelve cylinder engine, but I would have it understood that my invention is not limited to the disclosure shown, and that changes and modifications may be 50 made without departing from the real scope and spirit of the invention. In the drawings—

Figure 1 is a view in side elevation of the circuit breaker and distributor mechanism. 55 Fig. 2 is a horizontal sectional view taken

substantially on the plane of line 2—2 of Fig. 1.

Fig. 3 is a vertical sectional view of the circuit breaker and distributor unit, this view being taken substantially on the plane 60 of the line 3—3 of Fig. 2.

Fig. 4 is a diagrammatic representation of the entire ignition mechanism as applied to a twelve cylinder engine.

As a general understanding of the invention 65 can probably best be obtained by reference to the diagrammatic view showing the complete installation, attention is accordingly first directed to that figure. In this figure the cylinders of a twelve cylinder engine are 70 represented diagrammatically and are numbered 1 to 12. The combined circuit breaker and first distributor unit is designated 15. The second distributor unit is designated 16. An induction coil for one set of cylinders 75 is indicated at 17, and an induction coil for a second set of cylinders is indicated at 18. The battery or source of current is indicated at 19, and an automatic controlling switch is shown at 20.

The circuit breaker and distributor mechanism comprises in the present instance the two units 15 and 16, the first of which is made up of the circuit breakers and distributor for one coil, the other unit consisting simply of a distributor for the other coil. In its specific construction the first unit comprises a hollow body portion 22 for inclosing and supporting the several parts, and which is mounted upon and supported 80 by the engine-driven upright cam shaft 23. This cam shaft may be driven by bevel gearing 24 or the like, from the crank shaft 25 of the engine.

Within the hollow body of the interrupter 95 unit are mounted the circuit breakers comprising the breaker arms 26 and 27 pivoted on the stud 28 and carrying on their ends contacts 29 and 30 for engagement with the relatively stationary contacts 31 and 32. 100 The circuit breaker arms are forced over toward their relatively stationary contacts by the reflexed springs 33, which bear against a contact plate 34 on the inner wall of the body or housing. This contact plate is insulated from the housing by a sheet of insulation 35 interposed between it and the wall of the housing, and a terminal screw 36 extends through the wall of the housing into engagement with said contact plate, said 110

terminal being insulated from the housing, by insulating bushing 37.

The stationary breaker contacts 31 and 32 are carried by the terminal plates 40 and 41 mounted on insulating bases 42 and 43 within the housing. External terminals 44 and 45 are connected to these terminal plates, said terminals being insulated from the housing where they pass therethrough by the means of insulated bushings 46 and 47.

The pivoted breaker arms 26 and 27 are suitably insulated from each other and from the housing, in the present instance, by means of the insulating bushings 48 and insulating washers 49 on the pivot stud 28.

The circuit breaker arms are thus, by the means illustrated, pivoted one above the other in superposed relation and they are operated by two sets of cams arranged in superposed relation upon the cam shaft 23. The first or upper set of cams 50 operate by engagement with the roller 51 of the upper breaker arm 26 to actuate the first circuit breaker, and the second set of cams 52 on the cam shaft below the first set operate by engagement with the cam roller 53 of the second breaker arm 27 to actuate the second circuit breaker. The breaker arms may be insulated from the cam shaft by making the cam rollers of hardened insulating material. In the construction illustrated there are six cams in each set and the cams of one set are disposed in planes intermediate the cams of the other set. This cam shaft, for a four-cycle engine, rotates at half the crank shaft speed, thereby producing six breaks for every revolution of the crank shaft.

The relatively stationary contact points of the circuit breakers, are preferably made adjustable to take up wear, etc., as by making them in the form of screws, as indicated, which can be reached for purposes of adjustment through openings 55 in the side of the housing. To facilitate this adjustment, the housing may be made with an opening 56 in line with the contacting faces of the relatively stationary and movable contacts. These openings may normally be closed to keep out the dust, etc., by means of a sleeve 50 section 57 slidably engaged over the outside of the housing and operated by finger hold 58. This cover sleeve is cut out as indicated at 59 for the terminals 36—44 and 45, and this cut-out portion is made sufficiently large to allow for the rotative movement necessary to uncover the openings in the housing.

The cams for the circuit breakers may be formed directly upon the cam shaft, but preferably, these cams are formed on a shaft section substantially as indicated, made of steel and which is secured to the upper end of the cam shaft by means such as the set screws 60.

The circuit breaker mechanism may be

covered over at the top by a horizontal partition 61, which may be formed with a window 62 to give a view of the circuit breaker contacts.

The breaker unit is preferably mounted upon ball bearings such as indicated at 65, in Fig. 1. An upper ball bearing may be also provided and be carried by the horizontal cover or partition 61 as indicated at 66, the cam shaft being arranged to engage with these bearings.

The distributor portion of the first or breaker unit comprises in the illustration, a brush 70 mounted on the upper end of the cam shaft, and coöperating with or engaging with distributor points or contacts 71 on the interior of a cap 72 which is applied to the top of the unit. This distributor head or cap may be detachably secured to the housing or body of the device by means of spring clasps 73 engaging with studs 74 on the housing. The brush 70 is shown mounted in a metallic socket 70' seated in an insulating disk 75 secured in proper position on the upper end of the shaft. This brush socket has a contact spring 76 projecting upward into engagement with the point of a central terminal 77 on the distributor head. The brush segments or contacts 71 extend up through the top of the cap 72 to provide the external terminals 78, 79, 80, 81, 82 and 83.

The distributor 16 for the second coil and the second set of cylinders is, in the present disclosure, built as a unit separate and distinct from the first distributor, and is, in practice, a substantial counterpart or duplicate of the first distributor. Said distributor comprises an engine-driven shaft 85 rotating at the same speed as the first distributor and cam shaft 23 and bearing at its upper end a brush 86 to coöperate with or engage the distributor points or contact segments 87 in the distributor head 88. The distributing brush 86 is shown carried by an insulating head 89 mounted on the upper end of the shaft 85, and provided with a contact spring 90, the same as in the first distributor. In Fig. 2 I have indicated how springs 91 may be employed to force the distributor brushes yieldingly out into engagement with the segments. The segments 87 of the second distributor are provided on top of the cap with external terminals 92, 93, 94, 95, 96 and 97.

The two units of the interrupter and distributor mechanism are coupled together by means of a pivoted link 100 connected to outstanding arms 101 and 102 on the housings of the two units. A rod 103 is connected to one of the units for the purpose of shifting the same for advancing or retarding the spark.

With this description, the operation of the invention will be fully understood by refer-

ence to the diagrammatic view. In the position of the parts there indicated, the brush 86 of the second distributor is in engagement with the contact for the number 1 cylinder 5 and the circuit breaker which controls the coil that furnishes the current to the cylinder is in the act of or has acted to break the circuit to create a spark. The flow of current in the case supposed at the moment of 10 interruption is as follows: from current source 19, through conductor 105 to the thermostat 106 of the automatic switch 20, thence by conductor 107 to the primary 108 of the induction coil 18, conductor 109 to the 15 lower circuit breaker terminal 45, stationary contact 32, breaker arm contact 30, breaker arm 27, terminal plate 34, terminal 36, conductor 110 to ground 111, the other side of the current source being grounded as indicated at 112. The break in the primary circuit induces a high potential charge in the 20 secondary winding 115 of induction coil 18, the path of high tension current being as follows: from secondary 115 through conductor 116, to the center terminal 98 of the 25 second distributor, through brush 86 to the segment 87 of terminal 92, and from terminal 92 through high potential conductor 117 to the spark plug 118 of the number 1 30 cylinder, one side of this spark plug being grounded as customary, and the other end of the secondary being grounded, for instance, by means of the same ground 111.

Slight further rotation of the parts brings 35 the brush 70 of the first distributor into contact with the segment of the terminal 78. The first or upper circuit breaker operating at this moment to interrupt the current through the primary 120 of the first induction coil 17 induces a high potential charge in secondary 121, whereupon a high potential charge is sent through conductor 122 to the 40 spark plug on number 4 cylinder. The diagram, with this description, makes clear 45 the sequential firing of the other cylinders without specific reference to the detailed connections, attention merely being called to the fact that the primary current conductor 107 has a branch 125 leading to the primary of 50 induction coil 17, the other end of said coil being connected by conductor 126 to the circuit breaker terminal 44, while the secondary 121 is connected by conductor 127 with the center terminal 77 of the first distributor. 55 From the foregoing it will be evident that in my invention synchronism is entirely dependent upon the breaks in the primary circuits. The cams being correctly cut and the breakers being alike and mounted directly 60 one over the other then the only element which can effect the synchronism is the adjustment of the breaker points and these points are set so as to have them both open the same distance. This can be accomplished by 65 adjusting the contact screws so that they are

in line with each other and this can be done by the use of a thickness gage. After the mechanism is once installed this is the only adjustment which may ever be necessary.

My invention will be seen to provide reliable means for the regular ignition of engines having a comparatively large number of cylinders, which means is of a sturdy and simple construction, and not liable to get out of order, and in which the timing of the 75 firing of the various cylinders is maintained in proper synchronism.

What I claim is:

1. In a multi-cylinder ignition system, a shaft provided with cams, circuit breaker 70 arms superposed one above the other arranged to be operated by said cams, a distributor brush on the cam shaft above the cams thereon and a distributor head provided with contacts disposed in the plane of 85 movement of said brush.

2. In an ignition system for multi-cylinder engines, the combination of an engine-driven cam shaft, a set of cams on said cam shaft, a circuit breaker operated by said set 90 of cams, a second set of cams on the cam shaft, the cams of said second set being disposed in alternating relation to the cams of the first set, and a second circuit breaker operated by said second set of cams. 95

3. In a multi-cylinder ignition system, a combined interrupter and distributor unit including interrupters for all the cylinders of the engine and a distributor for one set of engine cylinders, an independent distributor 100 for a second set of the engine cylinders, and means coupling said independent distributor to the combined interrupter and distributor unit, whereby said two units are simultaneously adjustable for the purpose of advancing or retarding the ignition. 105

4. In a multi-cylinder ignition system, a shaft provided with cams, an interrupter housing surrounding said cam shaft, an upright pivot stud carried by said housing, 110 circuit breaker arms pivoted in superposed relation on said stud and arranged to be operated by the cams aforesaid, contacts carried by said arms and relatively stationary contacts in the housing arranged to be 115 engaged by said breaker arm contacts, certain of said contacts being adjustable with respect to the engaging contacts whereby the extent of break of the respective circuit breaker arms may be independently determined. 120

5. In a multi-cylinder ignition system, a cam shaft provided with one set of spaced cams and with a second set of spaced cams disposed above the first set and in alternating relation in respect to the cams of the first set, circuit breaker arms superposed one above the other and arranged to be respectively operated by the two sets of cams, a distributor brush on the cam shaft above 125 130

the cams thereon, and a distributor head provided with distributor points disposed in operative relation to said brush.

6. In a multi-cylinder ignition system, a cam shaft provided with one set of spaced cams and with a second set of spaced cams disposed above the first set and in alternating relation in respect to the cams of the first set, circuit breaker arms superposed one above the other and arranged to be respectively operated by the two sets of cams, a distributor brush on the cam shaft above the cams thereon, a distributor head provided with distributor points disposed in operative relation to said brush, a distributor shaft, a brush carried thereby, a distributor head provided with contact segments engaged by said brush and a link connection between said distributor head and the first distributor head.

7. In a multi-cylinder ignition system, a cam shaft provided with superposed sets of cams, an interrupter housing surrounding said cam shaft, a pivot stud carried by said housing, circuit breaker arms pivoted in superposed relation on said stud and arranged to be operated by the respective sets of cams, contacts carried by said arms and relatively stationary contacts in the housing arranged to be engaged by said breaker arm contacts.

8. In a multi-cylinder ignition system, a cam shaft, an interrupter housing surrounding said cam shaft, a relatively stationary contact carried by said housing, a circuit breaker arm pivoted in said housing, provided with a contact to engage the relatively stationary contact, said housing having a side opening in the wall thereof exposing said contacts, and a cover sleeve rotatably engaged on the housing provided with an opening arranged upon rotation of the sleeve to be registered with the side opening in the wall of the housing.

9. In an ignition system for multi-cylinder engines, the combination of an engine-driven cam shaft, a set of cams on said cam shaft, a circuit breaker operated by said set of cams, a second set of cams on the cam shaft, the cams of said second set being dis-

posed in alternating relation to the cams of the first set, a second circuit breaker operated by said second set of cams, a distributor arm on the cam shaft, and distributor points disposed about the distributor arm on the cam shaft.

10. In a multi-cylinder ignition system, an engine-driven combined interrupter and distributor unit including interrupting means for all the cylinders of the engine and a distributor for one set of engine cylinders, and a separate engine-driven distributor for a second set of the engine cylinders.

11. In a multi-cylinder ignition system, an engine-driven cam shaft, a set of cams on said cam shaft, a second set of cams on the cam shaft above the first set of cams thereon, an interrupter housing surrounding said cams, a circuit contact in the housing, a second circuit contact in the housing above the first circuit contact, a circuit breaker arm in the housing operated by the first set of cams and provided with a contact for engagement with the first circuit contact, and a second circuit breaker arm mounted in the housing above the first circuit breaker arm, said second circuit breaker arm being operated by the second set of cams and provided with a contact for engagement with the second circuit contact.

12. In a multi-cylinder ignition system, a cam shaft, an interrupter housing surrounding said cam shaft, a relatively stationary contact in said housing provided with means for adjusting the same, a circuit breaker arm movably mounted in said housing and provided with a contact to engage the relatively stationary contact, said housing being open in one side thereof to expose said contacts and the adjusting means for the relatively stationary contact, and a cover normally closing the open-sided interrupter housing to protect the contacts and contact adjusting means, said cover being movably engaged on the housing to thereby enable the exposure of the contacts and the contact adjusting means.

ERNEST C. WILCOX.
